UNITED STATES PATENT OFFICE.

ANNIE HOPKINS, OF LEWISTOWN, MONTANA.

SCISSORS.

1,017,545.

Specification of Letters Patent.

Patented Feb. 13, 1912.

Original application filed April 17, 1909, Serial No. 490,484. Divided and this application filed October 12, 1910. Serial No. 586,770.

To all whom it may concern:

Be it known that I, ANNIE HOPKINS, a citizen of the United States, residing at Lewistown, in the county of Fergus and 5 State of Montana, have invented a new and useful Scissors, of which the following is a specification.

This invention relates to scissors especially designed for use by dressmakers and it is 10 a division of an application filed April 17, 1909, and which issued on June 14, 1910, as Patent No. 961,235.

One of the objects of the invention is to provide the scissors with handles carrying 15 marking devices which are compactly and conveniently arranged so as to be readily used with but little manipulation in order to bring the parts into operative position.

With the foregoing and other objects in 20 view the invention resides in the combination and arrangement of parts and in the details of construction hereinafter described and claimed, it being understood that changes in the precise embodiment of invention herein disclosed can be made within 25 the scope of what is claimed without departing from the spirit of the invention.

In the accompanying drawings:—Figure 1 is a plan view of a pair of scissors or 30 shears having the present improvements combined therewith, portions of the handles being shown in section. Fig. 2 is an elevation of the handle portions of the shears. Fig. 3 is a section on line A—B, Fig. 1. 35 Fig. 4 is a section on line C—D Fig. 1.

1 and 2 designate the blades of the scissors, the blades being pivotally connected and provided with handles 3 and 4. Handle 3 has a finger ring 5 which, in the present 40 instance, is circular, and formed in the marginal portion of this ring is an annular groove 6 one end wall of which has a pocket 7 therein while the opposite end portion of the groove is covered by a retaining spring 45 8 secured to the handle 3 in any suitable manner. A curved piece of chalk 10 or other marking material, is seated within the groove 6 and has a tongue 11 at one end adapted to project into the pocket 7 while 50 another tongue 12 extends from the other end of the chalk marker and is adapted to be lapped and retained by the spring 8. The marker 10 projects beyond the marginal portion of the ring 5.

The handle 4 is provided with a tubular 55 finger ring 13 and an annulus 14 is housed within this ring and is adapted to rotate therein, the outer periphery of the annulus being formed with a continuous series of spurs 15. The outer edge of the finger ring 60 14 is cut-away for a portion of its length, as indicated at 16 so that a few of the teeth 12 are constantly exposed.

By providing scissors such as described, the same can be conveniently used for the 65 purpose of marking, the spur annulus 14 being always ready for use as a tracing wheel, or for such other purposes for which these devices may be used.

The marker 10 on the ring 5 is also at all 70 times ready for use, but, since the marker is subject to wear as a result of such use, it may be readily removed when worn down to the ring and a new piece substituted by a proper manipulation of the spring 8. 75

What is claimed is:—

1. A pair of scissors having an annular groove in one of the finger rings of the handles, and a marking device seated within the groove and projecting beyond the ring. 80

2. A pair of scissors having an annular groove in one of its finger rings, and a marking device mounted for movement within and projecting beyond the groove.

3. A pair of scissors having an annular 85 groove in the peripheral portion of one of its finger rings, and a curved marker movably mounted within and projecting from the groove.

4. A pair of scissors having a finger ring 90 upon one of its handles, and an annular spur wheel housed in said ring, and extending therethrough.

5. A pair of scissors including a finger ring upon one of the handles, said ring being 95 tubular and having a cut-away portion, and an annular spur wheel mounted for rotation within said ring and having a portion thereof projecting from the cut-away portion. 100

In testimony that I claim the foregoing as my own, I have hereto affixed my signature in the presence of two witnesses.

ANNIE HOPKINS.
